UNITED STATES PATENT OFFICE

HERBERT E. EASTON, OF PROVIDENCE, RHODE ISLAND, ASSIGNOR TO EASTON AND BURNHAN MACHINE COMPANY, A CORPORATION OF RHODE ISLAND

WARP BEAM WINDING MACHINE

Application filed April 18, 1932. Serial No. 605,809.

This invention relates to a warp beam winding machine, and has for its object to provide a drive for the beam which will not damage the yarn and which will be more positive than driving the beam through engagement with the yarn itself, especially where silk or rayon having a smooth shiny surface is operated on.

Another object of the invention is to provide a drive for a warp beam which will enable the operator to more easily locate and piece together a broken end.

Another object of this invention is the provision of a construction which will permit the warp beam to be easily handled and mounted in the machine or removed from the machine and yet rigidly secure the bearings for the warp beam when in operating position to prevent vibration.

A further object of the invention is the provision of means cooperating with the drive of the machine to vary the driving speed of the machine that the linear travel of the warp threads about the beam will remain substantially constant regardless of the increased diameter of the beam as the winding accumulates thereon.

A still further object of the invention is the automatic compensation of such variation in the speed of the drive which is operated by connection with the driving means itself.

With these and other objects in view, the invention consists of certain novel features of construction, as will be more fully described, and particularly pointed out in the appended claims.

In the accompanying drawings:

Fig. 1 is a side elevation of the machine, illustrating the warp beam in driving position.

Fig. 2 is an end view of the structure shown in Fig. 1.

Fig. 3 is a fragmental view showing the position of the warp beam as on the floor or support for the machine with the arms secured to the bearings in its lowered position.

Fig. 4 is a detailed view showing the power roll and driving roll for engaging

50 the head of the warp beam and illustrating

the swingably mounted arm for mounting the drive roll.

Fig. 5 is a detailed view illustrating the control for the automatic compensating means for varying the speed of the power roll.

In warp beam winding machines it is usual practice to drive the beam by engagement with the work itself in order that a constant linear travel of the warps may be had and when the work is stopped prior to completely filling the warp beam and the drive is picked up or started for a completion of the winding of the warps, I have found that such drive sometimes damages the yarn and when used upon warps having a shiny surface, such as silk or rayon, is apt to slip along the yarn as sufficient pressure cannot be applied to stop this and consequently there will be a certain amount of lost motion

60 and damaged yarn. I have also found that in removing warp beams from the winding machine, as the same may weigh in the neighborhood of five hundred pounds filled, that these beams are difficult and awkward

65 to handle, and in order to avoid these undesirable results and conditions above mentioned, I have driven the warp beam from the head thereof throughout its operation in the machine and compensated in the drive

70 to secure a constant linear speed for the warps at a maximum speed at which the warps may be run, and I have also provided

75 a mounting for the warp beam which permits it to be lowered after filled with yarn

80 to the floor or support for the machine to be there disconnected from its bearings and

85 rolled away to some convenient place for handling, and by this arrangement I permit a new warp beam to be positioned in

90 its bearings while resting on the floor and then raised to its driving position and held

95 securely in this position, the raising being accomplished by guiding means which en-

gage the head of the warp beam and por-

100 tions attached to the arms; and the follow-

ing is a detailed description of the present embodiment of this invention illustrating

the preferred means by which these advan-

105 tageous results may be accomplished.

- With reference to the drawings, 10 designates a frame standard of the machine which is provided with feet 11 to rest upon the floor or other convenient support 12. Two such standards 10 are provided and between these standards there extends suitable braces for maintaining them in position, and along the upper edge of the machine there is provided a guide roll 13 over which the warps 14 are guided to the warp beam which is designated generally 15 and which consists of opposite heads 16 at the ends of a barrel portion 17.
- Arms 18 are provided at each side of the machine which have bearings 19 at their ends with a separable cap portion 20 to be removed for mounting or dismounting a warp beam to or from position, the same being provided with an axle 21 in said bearing. These arms are connected at their upper ends to a lever 22 which is keyed to the shaft 23 and which is rotated by means of a worm wheel 24 and worm 25 by a suitable crank 26 having a handle 27.
- As illustrated in Fig. 3, the beam is in position on the floor and the arm is in lowered position with the axle 21 mounted in the bearing 19. Upon turning the crank handle 27 to operate the gears 24 and levers 22, the arms 18 are drawn upwardly and swung outwardly by reason of the heads 16 of the beam engaging the guide and brace rod 28 extending between opposite frame supports 10 of the machine. This guide causes the beam to be lifted substantially vertically while rolling about the guide 28 and is so positioned that the pins 29 on the arms will be guided into a position to engage the cam surfaces 30, as illustrated in dotted lines at 31 and thence as the arms 18 are drawn upwardly the pins 29 will move into the sockets 32 provided for them on the frame of the machine and maintain the arms in a firm relation to the machine, and rigidly rotatably mount the beam in its driving position to prevent chattering or vibration.
- The sole driving means for the beam in my present machine is through the heads of the beam by some resilient means and to accomplish this I have provided an elongated power roll 33 which is driven from a suitable source of power by a pulley 34. I mount arms 35 to pivot about the axis 36 of this power roll 33 as a center and at the outer end of these arms are resiliently supported rubber surfaced drive rolls 37 allowing some yield and held in engagement with the power roll 33 by means of a spring 38.
- These rolls are mounted in suitable bearings in the ends of the arms 35 by means of an axle 39, and the arms 35 supporting this drive roll are swung about the axes of the power roll as a center by means of a spring 40 to yieldingly maintain the drive

roll in engagement with the edge of the beam head 16 during its driving action.

The swinging arms 35 mounting these drive rolls are limited in the movement caused by the spring 40 so that when the beam is removed from position the drive rolls will be maintained in substantially the position illustrated in Fig. 3, and in which position the beam will engage these rolls as it is moved upwardly as above described and swung against these rolls to move them slightly and the arms upon which they are mounted by yielding of the springs 40 so that firm engagement of the parts is maintained.

The pulley 34 is driven by a suitable belt 41 from a motor 42 and on this motor there is provided a specially constructed pulley 43 formed of two inwardly bevelled or inclined disks which are forced together by a spring 44a. The belt 41 is inclined on its edges or generally V shaped on its edge to fit the inclined surface of the disk 43 so that the speed of driving will be varied, dependent upon the amount the belt is forced inwardly toward the center of the pulley 43, and this amount of movement toward the center is dependent to some extent upon the tension of the belt; in other words, if the motor 42 and its pulley 43 will be moved further from the pulley 34, the belt would move inwardly toward the center of the pulley 43 by reason of the expansion permitted between the disks by the spring 44a, and I have utilized this construction to vary the drive of my beam in order to maintain a linear speed on the warps substantially constant; thus I have provided a mounting block 44 which slidably mounts the base 45 of the motor 42 and to this base there is connected a rack bar 46 having engagement with a spur gear 47 which is driven by a worm gear 48 and worm 49, while the worm 49 is driven by a worm wheel 50 and worm 51 on the axle of the power roll 33, so that as the power roll drives the roll 37 which in turn drives the warp beam, the motor will be gradually moved away from the power roll 33, thus drawing the belt 31 inwardly between the disks and decreasing the speed of the power roll and consequently the speed of the driving rolls and the warp beam, so that a substantially constant linear speed of the warps will be maintained even though a larger diameter of the work is being accumulated about the beam.

From this above it will be apparent that I have provided a drive for the warp beam by which the head only of the warp beam is driven and which drive is particularly adapted for a mounting of the warp beam so that it may be raised or lowered from position to be rolled to or from the machine and mounted in its bearings prior

to its being moved to its driving position. By this arrangement with the drive out of contact with the yarn, and there should be a slip between the beam and the drive, then 5 the driving cylinder will not polish the yarn as where the drive is in contact with the yarn and so will not injure the same. Also I find that this arrangement is such that a slack end of the warp will drop away 10 from the work where it may be easily observed by an operator rather than being rolled in on the beam as has heretofore occurred.

The foregoing description is directed 15 solely towards the construction illustrated, but I desire it to be understood that I reserve the privilege of resorting to all the mechanical changes to which the device is susceptible, the invention being limited only 20 by the terms of the appended claims.

I claim:

1. In a warp beam winding machine, a warp beam having heads, and a driving roll having an elastic surface positioned to engage 25 the edge of one of said heads to turn the same for winding of warp threads or the like thereon.

2. In a warp beam winding machine, a warp beam having heads, and a driving roll having an elastic rubber surface positioned 30 to engage the edge of one of said heads to turn the same for winding of warp threads or the like thereon.

3. In a warp beam winding machine, a warp beam having heads, a driving roll, a pivoted arm to mount the driving roll and swing the same into engagement with one 35 of said heads for driving the warp beam to wind warp threads or the like thereon, a power roll to drive said driving roll, said arm mounted to swing about the axis of the power roll, resilient means to move said arm to cause the driving roll to maintain driving engagement with said head, and driving 40 means for said power roll, said means including means for progressively varying the speed of said power roll.

4. In a warp beam winding machine, a warp beam having heads, a driving roll, a pivoted arm to mount the driving roll and swing the same into engagement with one 45 of said heads for driving the warp beam to wind warp threads or the like thereon, a power roll to drive said driving roll, said arm mounted to swing about the axis of the power roll, resilient means to move said arm to cause the driving roll to maintain driving engagement with said head, and means for driving 50 said power roll to maintain a substantially constant travel of the yarn about said beam.

5. In a warp beam winding machine, a warp beam having heads at the ends thereof, a pair of movable arms, bearings for said beam on said arms, a drive roll engaging

said beam to rotate it, means to move said arms to move the beam from engagement with said drive roll and position it on the floor or support for said machine, and a guide substantially above the level of said 70 floor engaged by said beam to assist in directing its path of movement.

6. In a warp beam winding machine, a warp beam having heads at the ends thereof, a pair of movable arms, bearings for 75 said beam on said arms, a drive roll, a pin on each of said arms, sockets for said pins fixed on the frame of the machine, means to move said arms to a position to permit a beam resting on the floor or support to be mounted in said bearings, and then raise the arms to position said pins in said sockets and at the same time move the beam into engagement with said drive roll, whereby the bearings for said beam are 80 fixed during the operation of the beam on the machine.

7. In a warp beam winding machine, a warp beam having heads at the ends thereof, a pair of movable arms, bearings for 85 said beam on said arms, a drive roll, a pin on each of said arms, sockets for said pins on the frame of the machine, a cam surface leading to said socket, means to move said arms to a position to permit a beam resting on the floor or support to be mounted in said 90 bearings, and then raise the arms to position said pins in said sockets, and at the same time move the beam into engagement with said drive roll.

8. In a warp beam winding machine, a warp beam having heads at the ends thereof, a pair of movable arms, bearings for 95 said beam on said arms, a drive roll, a pin on said arms, a socket for said pin on the frame of the machine, a cam surface leading to said socket, means to move said arms to a position to permit a beam resting on the floor or support to be mounted in said 100 bearings, and then raise the arms to position said pin in said socket and at the same time move the beam into engagement with said drive roll, and a guide to engage the head of said beam to lift the pin into engagement with the cam surface and the beam from its 105 floor or support.

9. In a warp beam winding machine, a warp beam having heads at the ends thereof, a pair of movable arms, bearings for said beam on said arms, a drive roll, a pin on said arms, a socket for said pin on the frame of the machine, a cam surface leading to said socket means to move said arms to a position to permit a beam resting on the floor or support to be mounted in said 110 bearings, and then raise the arms to position said pin in said socket and at the same time move the beam into engagement with said drive roll, and a brace for extending between the ends of said machine so positioned 115

- as to be engaged by the head of said beam to guide the lifting of the same and the arms so that said pin will engage said cam surface to move into said socket.
- 5 10. In a warp beam having heads with journals extending outwardly therefrom, bearings for said journals, means for rigidly mounting said bearings during the working operation of said warp beam, and a roll
- 10 10 having an elastic surface for engaging and frictionally driving the head of said warp beam.
11. In a warp beam winding machine, a warp beam, means out of contact with the work on the beam for driving the beam, said means including means free from contact with the work for progressively decreasing the speed of the warp beam proportionate to the accumulation of yarn on the beam whereby an even rate of winding is maintained.
- 15 12. In a warp beam winding machine, a warp beam having heads, a driving roll engaging one of said heads for driving the warp beam to wind warp threads thereon, means free from contact with the work for driving said driving roll at a progressively decreasing speed to maintain the drawing of the warp threads wound about the beam at a constant rate of speed.
- 20 13. In a warp beam winding machine, a warp beam having heads, a driving roll engaging one of said heads for driving the warp beam to wind warp threads thereon, a motor, a pair of yielding flaring disks operated thereby, means driving said driving roll including a belt having inclined sides to fit between said disks, and means for
- 25 30 means free from contact with the work varying the distance of said motor and disks from said drive roll to vary the speed thereof.
- 35 14. In a warp beam winding machine, a driving roll, a pivot arm to mount the driving roll, spring means to swing the driving roll towards and past operating position, a warp beam having heads, means for moving said beam to operating position and by said movement cause one of its heads to engage
- 40 50 said driving roll and swing the arm mounting it about its pivot whereby resilient driving engagement is had for winding warp threads or the like on said beam.
- 45 15. In a warp beam winding machine, a driving roll, a power roll to drive said driving roll, a pivot arm to mount the driving roll, said arm being mounted to swing about the axis of the power roll, spring means to
- 55 60 swing the driving roll towards and past operating position, a warp beam having heads, means for moving said beam to operating position and by said movement cause one of its heads to engage said driving roll and swing the arm mounting it about its

pivot, whereby resilient driving engagement is had for winding warp threads or the like on said beam.

In testimony whereof I affix my signature.
